Primary Examiner — Paul D Bohannon

CLAIM

The ornamental design for a sideboard cabinet, as shown and described.

DESCRIPTION

FIG. 1 is a front, left and top perspective view of a sideboard cabinet showing my new design;

FIG. 2 is a front, right and top perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

The broken lines illustrate portions of the article that form no part of the claimed design.

1 Claim, 8 Drawing Sheets
